(57) **CLAIM**

We claim the ornamental design for remote digital motor sentry keypad, as shown and described.

DESCRIPTION

FIG. 1 is a perspective view of one embodiment of the invention;

FIG. 2 is a front view of the embodiment of FIG. 1;

FIG. 3 is a front view of FIG. 1 wherein the unclaimed subject matter of the lower controls are shown in a different arrangement;

FIG. 4 is a left side view of the design;

FIG. 5 is a right side view of the design;

FIG. 6 is a top plan view of the design; and,

FIG. 7 is a bottom view of the design.

The mounting cable and housing support shown in phantom in FIG. 1 are for illustrative purposes only and form no part of the design. The lettering and arrow designations in each of the FIGS. 1-3 are for illustrative purposes only and form no part of the design. The back side view of the design is not shown and is disclaimed.
